UNITED STATES PATENT OFFICE.

WAYNE B. STANDEE, OF MERIDIAN, TEXAS.

EXTENSION BROOM-HANDLE.

1,194,894.

Specification of Letters Patent. Patented Aug. 15, 1916.

Application filed February 1, 1916. Serial No. 75,548.

To all whom it may concern:

Be it known that I, WAYNE B. STANDEE, a citizen of the United States of America, and resident of Meridian, in the county of Bosque and State of Texas, have invented certain new and useful Improvements in Extension Broom-Handles, of which the following is a specification.

This invention relates to extensions for broom handles and devices of that character, and the said invention has for its object the provision of novel means whereby sections of handles may be joined together for increasing the length of the handle as when the broom is to be used for cleaning walls, ceilings and the like and it may furthermore be employed for splicing broken or impaired handles.

A further object of this invention is to provide a clamp preferably having an extension secured permanently in place, the said clamp having means whereby the sections thereof may be drawn together to create a rigid joint between the extension 25 and the ordinary handle of a broom.

A further object of this invention is to provide means whereby the members or sections of the clamp may be expeditiously operated to produce the clamping action 30 and it is furthermore an object of this invention to provide a clamp with a tapered socket or seat for the reception of the broom handle so that the said clamp may accommodate itself to handles, although said 35 handles are not uniform in their cross sectional area throughout their lengths.

With the foregoing and other objects in view, the invention consists in the details of construction and in the arrangement and 40 combination of parts to be hereinafter more fully set forth and claimed.

In describing the invention in detail, reference will be had to the accompanying drawings forming part of this specification 45 wherein like characters denote corresponding parts in the several views, and in which—

Figure 1 illustrates a view in elevation of a fragment of a broom handle showing 50 the extension clamp and a fragment of the extension applied thereto, the said clamp being shown in section; Fig. 2 illustrates a view in elevation of one of the clamping sections; and Fig. 3 illustrates a sectional view on a line corresponding with the line 3-3 of Fig. 2.

In these drawings 4 denotes a broom handle, which as they are now made is increased in thickness toward the end, thus making what may be termed a flared handle; 5 illustrates a fragment of an extension for increasing the length of the said handle and 6 and 7 denote clamping sections which are secured to the handle by means of the bolt 8 which enters the apertures 9 and 10 so that as the said bolt is rotated, it draws the sections of the clamp together or releases the said sections according to the direction of rotation of the bolt. The interior surface of each clamp section is of novel configuration in that it is increased in width from the end toward the center portion thereof so that when the two clamping sections are brought together, the socket or seat formed by the two clamping sections is larger at the center of the clamp than it is at the end thereof and as explained heretofore, this is done to accommodate the broom handles which are now commonly made larger at the top than at 80 points intermediate the length.

The extension 5 is likewise held by the clamping sections 6 and 7 and provision is also made for retaining the said extension in place, in that each clamping section has 85 an aperture 11 for the reception of a screw 12 which screw is embedded in the extension 5. The manipulation of the clamping sections for the purpose of applying or removing the broom handle does not interfere 90 with the anchorage between the screws 12 and the extension as the movement of the clamping sections with relation to each other in order to create a clearance for the broom handle is so slight as not to interfere 95 with the fastening between the clamping sections and the said extension.

The clamping sections preferably taper at the ends as shown at 13 and 14, this being accomplished by reducing the thickness of 100 the clamps toward the ends; and the recesses or inner seats of the clamping sections are preferably so arranged that when the clamping sections are applied to the broom handle and to the extension, there is 10 a space between the edges of the clamping sections to permit movement of one section with relation to the other under the influence of the action of the screw 8.

I claim:

In an extension broom handle, clamping sections each having recesses in their inner

22
sides, the recesses for the reception of the broom handle being of increased area of cross section from the end toward the center thereof and conforming to the contour of 5 the upper end of the handle, an extension seated between the clamping sections, screws in the clamping sections and embedded in the extension, one of said sections having a threaded aperture and the other of said 10 sections having an aperture with plain walls, a screw rotatable in the last men-

tioned aperture and threaded in the first mentioned aperture for drawing the clamping sections into engagement with the broom handle and the extension. 15

In testimony whereof, I affix my signature in the presence of two witnesses.

WAYNE B. STANDEFER.
